Filed Dec. 2, 1964, Ser. No. 82,874

Term of patent 14 years

(Cl. D61—1)

Fig. 1.

Fig. 2.

Fig. 3.

Fig. 4.

FIG. 1 is a perspective view of a combined motion picture projector and carrying case therefor with the case closed, taken from the front and one side, and showing my new design;

FIG. 2 is a perspective view corresponding to FIG. 1 and showing the case open for use of the projector;

FIG. 3 is a rear perspective view of the machine as seen in FIG. 2; and

FIG. 4 is a side elevation view thereof with the case open.

The bottom of the combined motion picture projector and carrying case therefor is substantially plain and unornamented.

I claim:

The ornamental design for a combined motion picture projector and carrying case, as shown and described.
